UNITED STATES PATENT OFFICE.

LERoy S. PFOUTS, OF CANTON, OHIO, ASSIGNOR TO THE MILLER PASTEURIZING MACHINE COMPANY, OF CANTON, OHIO, A CORPORATION OF NEW JERSEY.

PASTEURIZING APPARATUS.

1,185,532.

Specification of Letters Patent.

Patented May 30, 1916.

Original application filed January 9, 1913, Serial No. 740,940. Divided and this application filed October 15, 1913. Serial No. 795,277.

To all whom it may concern:

Be it known that I, LEROY S. PFOUTS, a citizen of the United States, residing at Canton, in the county of Stark and State 5 of Ohio, have invented certain new and useful Improvements in and Relating to Pasteurizing Apparatus, of which the following is a specification.

This invention relates to pasteurizing apparatus, and particularly to apparatus adapted to treat liquid, such as milk.

I have illustrated my invention in connection with a liquid treating apparatus such as shown and described in my application filed January 25, 1909, Serial No. 474,128. It will be understood, however, that my improvements in liquid distributing and holding mechanism for pasteurizing apparatus may be used in connection with 20 a liquid treating apparatus of any suitable or preferred construction and while the embodiment of the invention illustrated herein has been conformed to coöperate with the general construction of apparatus shown 25 in my said application, it may be adapted to suit any particular construction of apparatus in connection with which it may be used.

This application is a division of my application Serial No. 740,940, filed January 9th, 1913, patented October 31, 1913, No. 1,076,604.

Referring to the drawings, which show one embodiment of the invention: Figure 1 is a side elevation of my apparatus operatively connected with the liquid treating apparatus described in my aforesaid application, Serial Number 474,128. Fig. 2 is a side elevation, partly in section, of the 40 liquid distributing and holding mechanism. Fig. 3 is a horizontal section through the valve mechanism. Fig. 4 is a perspective view of one of the valve members. Fig. 5 is a perspective view of the other valve member. Fig. 6 is a bottom plan view of the valve mechanism.

In the drawings, A indicates a heater for the liquid, B a preliminary cooler, and C a final cooler, each of which is shown merely b, for the purpose of illustration.

D indicates as a whole a liquid distributing and holding apparatus, preferably interposed between the heater A and preliminary cooler B. The heater A, holding

apparatus D, and coolers B, C, are preferably arranged in stepped relationship to each other in order that the liquid may flow by gravity from one to the other and finally be discharged by the discharge pipe, indicated at c, carried by the final cooler C, into any suitable receptacle. Preferably the floor 1 for the apparatus D is elevated, as shown at 1^a, to provide for the proper flow of the liquid therefrom to the preliminary cooler B.

The heater A comprises an inner rotary vessel a² connected with a driven shaft a and adapted to hold a heating medium; an intermediate vessel a⁴ surrounding the vessel a²; and forming therewith a liquid film 70 space a⁵; and an outer vessel a⁶, surrounding the inner and intermediate vessels a², a⁴ and adapted to form with the outer walls of the latter vessel a chamber to receive a suitable heating medium.

The shaft a is geared to a driving shaft a⁷, which is mounted in bearings in a pedestal a⁸; the shaft a⁷ may be driven by a suitable motor, such as indicated at a⁹.

Each of the coolers B and C comprises an inner rotary vessel b², connected with a driven shaft b; an intermediate vessel b³, and an outer vessel b⁴. These vessels are constructed and arranged relatively to each other to form a liquid film space, and a 85 space or chamber on opposite sides of the film space for a suitable cooling medium.

The shafts b, of the coolers B, C, are connected to and driven by a driving shaft c⁴ which is mounted in bearings provided 90 therefor in the base, indicated at c³, on which the preliminary and final coolers, B, C, are mounted. The shaft c⁴ may be driven from any suitable source of power, such as a motor c⁵.

The heater A, and coolers B and C, are constructed, generally, and operate similarly to corresponding parts shown and described in the patent issued to John C. Miller on the 4th day of February, 1908, and numbered 878,225; and as the particular construction of each thereof forms no part of the present invention, further description of these parts will be omitted, as they are fully shown and described in the aforesaid 100 patent, to which reference may be made.

Of the distributing and holding apparatus D, 2 indicates a base of any suitable con-

struction, but preferably formed from metal and having feet 2^a. 2^b indicates a support, preferably bolted to the underside of the base 2 and provided with an axially arranged end thrust bearing or socket 2^c for the lower end of a vertical supporting rod 3. The rod 3 extends upwardly a suitable distance and carries at its upper end a valve member 4^a, of a valve mechanism 4 which will be later described. The member 4^a is provided with a socket 4^{a'} which receives the upper end of the rod 3 and permits angular adjustment of the member 4^a thereon.

2^a indicates an annular wall surrounding the rod 3. This wall is mounted on the base 2 and is preferably formed integral therewith. It serves as the shaft or axle for a rotary member 5, the hub 5^a of which rotatably fits the annular wall or shaft 2^a. At the point of connection between the wall 2^a and base 2, a bearing shoulder 2^e is provided, and interposed between said shoulder and the adjacent or lower end of the hub 5^a are anti-friction bearings of a well known type on which the rotary member 5 is rotatably supported.

The rotary member 5 preferably comprises a carrier 5' having a plurality of arms 5^b, which preferably extend radially, a series of brackets 5^c, one of which is carried by each radial arm 5^b, and an annular table or support 5^d supported concentrically of the axis of the rotary member 5 by the upper or free ends of the brackets 5^c.

35 The carrier 5' and hub 5^a may be formed integrally. The upper sides or faces of the arms 5^b are substantially flat and serve as bases to which the brackets 5^c are bolted in a well known manner. The arms 5^b may be provided with front and side walls 5^{b'}, which strengthen them from end to end. The arms 5^b are uniformly spaced from each other around the axis of the rotary member 5 and thus provides supports for the table 5^d around its entire circumference.

5^e indicates members depending from the arms 5^b, to the lower flanged ends of which is secured a worm gear 7, by screws or bolts 7' in a well known manner.

50 7^a indicates a bracket, carried by the base 2 and provided with bearings for one end of a driving shaft 7^b.

7^c indicates a worm or screw secured to the shaft 7^b and meshing with the worm gear 7^e to continuously drive the latter.

7^d indicates an auxiliary support, preferably adapted to be fixed to the floor 1^a. This support is provided with suitable bearings to receive and support the opposite end of the shaft 7^b.

7^{d'} indicates a motor, of any suitable type, which, through suitable gearing indicated as a whole at 7^e, transmits motion to the shaft 7^b.

65 As will be clearly understood from the

drawings, the gearing 7^e and the worm 7 and the worm screw 7^c serve as reduction gearing, whereby the speed of the rotary member 5, as compared with that of the motor 7^{d'}, is relatively slow.

70

The brackets 5^c are preferably arranged to incline or extend outwardly so as to provide supports for a table 5^d of relatively large size, their free ends being horizontal in order to support the table in a horizontal plane.

75

The table or annular support 5^d preferably comprises a series of arc sections 5^{d'} arranged end to end and each flanged along its opposite side edges to strengthen it. The sections of the table 5^d are preferably bolted to the brackets 5^c in a well known manner.

80

5^f indicates a plurality of openings formed in the table 5^d adapted to receive a series of independent or separate holding vessels 8. The openings 5^f are preferably uniformly spaced from each other and disposed midway between the brackets 5^c.

85

The valve mechanism 4 includes a valve seat element 10 which co-operates with the valve member 4^a to control the flow of the liquid to and from the vessels 8. The valve member 4^a preferably comprises a circular plate 4^{a''} provided with a depending rim or wall 4^x, which may be of conical shape. At one side and between the plate 4^{a''} and rim 4^x, the walls of the valve member 4^a are thickened and formed with two ducts 4^b, 4^c. The duct 4^b serves as the conduit for the liquid as it flows to the vessels 8, its inner end opening upwardly and centrally of the valve member 4^a and its opposite or outer end leading through the rim 4^x. The duct 4^c conducts the liquid through the valve member when a vessel 8 is emptying, its receiving end or port leading through the rim 4^x, and preferably adjacent to the port of the duct 4^b, and its opposite or discharge port opening downwardly as shown in the drawings. The valve seat element 10 preferably comprises a ring member formed with a series of openings 10^a, corresponding in number to the number of holders or vessels 8 and each adapted to register successively with the ports of the ducts 4^b, 4^c, in the member 4^a as said ring member rotates thereon.

110

The inner wall of the ring member is shaped to snugly fit the outer conical wall of the member 4^a to prevent leakage of the liquid.

115

10^b indicates a series of pipe sections, preferably formed integral with the ring member 10 and extending radially therefrom, there being a pipe section for each opening 10^a. The function of the pipe sections will be later described.

120

The vessels 8 may each comprise inner 125 and outer walls to form a space between them. This space may be filled with cork, as shown at 8^a, or some other non-conductor of heat to provide a suitable insulating jacket. Each of said vessels is preferably 130

provided with a detachable cover 8^b, and a duct 8^c in its bottom; a suitable pipe section 8^d being provided for said duct and adapted for conveying the liquid to and from the vessel as will be later described.

8^e indicates a flanged ring secured to the outer wall of each vessel 8. As will be understood from the drawings, when a vessel 8 is inserted in an opening 5^f, the flange of 10 the ring 8^e will engage with the upper surface of the table 5^d and serve to maintain the vessel 8 thereon. This construction 15 serves to support the vessels in upright position and to permit their removal at will for cleaning or other purposes.

9 indicates a receiving chamber preferably arranged substantially axially of the holders 8 and slightly elevated relative thereto to permit the variable flow of the liquid 20 by gravity to the holders. The chamber 9 is provided with a suitable cover through which extends the discharge end of a pipe 10^a, which conducts the liquid in a substantially continuous and uniform manner from 25 the liquid trough or discharge duct of the heater A to the chamber 9 of the distributing and holding apparatus D. The chamber 9 is preferably formed in two parts, an outer member 9^a, and an inner member 9^b, 30 between which is provided a suitable insulating jacket 9^c. The jacket 9^c serves to maintain the liquid in its heated condition. The chamber 9 is provided with an outlet pipe section 9^d, which is detachably connected to the upper end of a conduit 9^e, by a coupling 9^f. The lower end of the conduit 9^e is detachably connected in a well known manner to a coupling 9^g which in turn is screw threaded in the inner end or 40 opening of the duct 4^b. The pipe or conduit 9^e and its connections with the chamber 9 and valve member 4^a may serve in part as suitable means for rigidly supporting the chamber 9 upon the base 2 and at a suitable 45 height to effect the flow of the liquid through the apparatus.

11 indicates a depending discharge pipe connected with the discharge end of the duct 4^c. At its lower end, the discharge 50 pipe 11 is connected with a delivery pipe 6 which conducts the liquid to a receiver 12, the flow of liquid through the pipes 6 and 11 from the holders being variable. A cut off cock or valve 6^a may be provided for the 55 pipe 6.

12^a indicates a discharge pipe leading from the receiver 12 and arranged to convey the liquid in a substantially continuous and uniform manner to the receiving tank b⁵ 60 for the preliminary cooler B. A valve 12^b may be provided for controlling the flow of liquid from the receiver 12 to the tank b⁵.

The receiver 12 is preferably mounted on a standard 12^b. It may be dispensed with 65 if desired, in which event the liquid will be

conducted directly to the tank b⁵. The tank b⁵ permits the liquid, after treatment in the holding apparatus D, to be inspected.

10^e indicates a pipe, leading from the outer end of each pipe section 10^b to the adjacent vessel 8. As shown in the drawings, the outer end of the pipe 10^e leads to and is connected with the pipe section 8^d of the vessel 8 by a T-member 10^a and coupling 10^e. The opposite or inner end of the pipe 10^e is connected to the outer end of the pipe section 10^b by a coupling 10^f in a well known manner.

The pipes 10^e and their unions with the vessels 8 and pipe sections 10^b serve as rigid 80 connections between the valve seat member 10 and vessels 8, whereby the revolving movement of the latter is transmitted to the valve element 10 in order that the latter will move with the vessels, as a unit. 85

From the foregoing description it will be understood that the ring member 10 and walls of the member 4^a constitute a valve mechanism which controls the flow of the liquid through the pipes 10^e, to and from 90 the vessels 8 as each opening 10^a successively registers with the openings of the ports 4^b, 4^c.

During the time that the valve port 10^a for an adjacent vessel 8 registers with the duct 4^b, as the vessel revolves, liquid will 95 flow therethrough from the chamber 9 to the vessel to fill the same, the speed of the rotary member 5 and the size of the valve openings 4^b being proportioned so that during the registry thereof sufficient liquid will 100 flow through the valve to substantially fill the vessel.

The liquid is held in the vessel 8 during its revolving movement until its valve opening 10^a registers with the port of the discharge duct 4^c, whereupon the liquid will flow by gravity from the vessel through the valve opening 10^a and duct 4^c to the discharge pipe 11. As the ducts 4^b, 4^c, and the valve ports thereof are of substantially the 110 same size, and the rotary member 5 rotates uniformly, it will be understood that substantially the same quantity of liquid will flow out of each vessel as flowed into it in the same time interval. 115

The valve port for the duct 4^c, is preferably arranged in the rim 4^x immediately behind the valve port for the duct 4^b, so that the filling operation for each vessel will follow immediately after it has been 120 emptied. This arrangement also provides for the operation of filling and emptying adjacent vessels simultaneously.

As the vessels 8 are arranged in a circular series and revolve around the valve member 4^a, provision is made for bringing a vessel into filling position immediately after the preceding vessel has been filled and moved out of that position in order that the filling operation may be progressive, 125 130

likewise by providing a discharge duct with which the valve ports for the vessels register successively provision is made for emptying the vessels in a progressive manner. 5 While the effect of this construction and operation is to produce a more or less variable and intermittent flow of the liquid through the apparatus, the apparatus may be so proportioned to the apparatus to 10 which it delivers as to give completely satisfactory results in connection therewith.

13 indicates a pipe or conduit leading from the pipe a^{10} and connected at its outer end to a delivery pipe 6^b . A valve, preferably of the three-way type may be interposed at the connection of the pipe 13 with the pipe a^{10} to control the flow of the liquid to either the distributing and holding apparatus or direct to the cooler B, or to cut 20 off the flow of the liquid entirely. The pipes 13 and 6^b may be used to conduct the liquid from the heater A to the cooler B, when it is unnecessary to treat the liquid in the distributing and holding apparatus D. 25 The pipes 6^b and 13 may be formed in sections and connected together by couplings 13^a in a well known manner.

It will be understood that in the system 30 of pasteurizing liquid to which my invention is particularly applicable, and in which the liquid is maintained at a pasteurizing temperature for a predetermined period, it is desirable to quickly and uniformly heat the liquid to the predetermined temperature, 35 maintain the liquid at that temperature for a certain definite length of time in order to destroy or render innocuous any germs or bacteria contained in the liquid, and finally to cool the liquid to a normal 40 temperature; and that it is also desirable that these steps shall be carried out in a progressive manner, that is, that there shall be a substantially continuous flow of the liquid to and through the heater, and from 45 the heater to the holder. The holder, however, may deliver or discharge the milk in a more or less variable and intermittent manner. These results are all accomplished in the apparatus herein described and illustrated, as will be more fully understood 50 from the following described operations: The liquid is delivered to a receiving tank having a discharge pipe A' , which operates as a supply means and from which it 55 flows by gravity to the heater A. In passing through the heater the liquid is suddenly and uniformly raised to the desired temperature and is discharged from the heater by means of the pipe a^{10} , which conveys the liquid in a continuous and uniform 60 manner to the receiving chamber 9. As the carrier 5 and vessels 8 carried thereby revolve, the valve openings 10^a in the ring valve 10 register successively with the 65 duct 4^b of the valve member 4^a and per-

mit a predetermined quantity of the liquid to flow variably by gravity to each of the vessels, each valve port registering with the duct for a given period of time, in the rotary movement of the carrier, sufficient, 70 at least, to substantially fill the adjacent vessel. Likewise, the valve openings 10^a of the valve ring 10 register successively with the discharge duct 4^c and permit the automatic discharge of the vessels successively. 75

The valve duct 4^c of the valve mechanism 4 may be arranged at any predetermined point angularly of the axis of the carrier relative to the port 4^b, so that the distance 80 of travel of the vessels from the position for filling to the position for emptying may be of proper length in order that the period for holding the liquid may be fixed according to any particular circumstances desired. 85 From this construction and operation it will be seen that the vessels will be automatically filled and emptied at predetermined points, and that the liquid in each vessel will be held therein for a predetermined period, 90 the extent of which depends upon the length and time of travel from the place of filling to the place of discharge. It will be obvious that the speed of the carrier can be changed in various ways to increase or decrease the period between the filling and emptying of the vessels. 95

The tank 9, being disposed between the heater A and the distributing and holding apparatus D, permits the material to flow 100 in a variable manner to each of the tanks 8, successively, without affecting its continuous and uniform flow from the heater A through the pipe a^{10} . It will be understood that as 105 the port 4^b moves into and out of registry with each opening 10^a, the flow of the material is at first very slow and gradually increases until the port 4^b and opening 10^a are in complete registry; then the flow of material gradually decreases until it is entirely 110 cut off by the continued rotation of the valve seat member 10; as a result of this operation the material is caused to flow in a variable manner from the tank 9 during the filling of each vessel 8, first starting from zero and increasing until a maximum flow is reached 115 and then decreasing back to zero. Thus the tank 9 serves as a means to permit the change of flow of the material from the heater A to distributing and holding apparatus D, so 120 that the flow of the material through and from the heater may be continuous and uniform. Likewise the tank 12 (or the receptacle b^a when the tank 12 is dispensed with) serves as a means to permit the material, 125 which flows in a variable manner from the distributing and holding apparatus D through the pipe 6, to flow to and through the coolers B, C, in a substantially continuous and uniform manner. 130

It will thus be seen that I have provided means on opposite sides of the distributing and holding apparatus D which first permit the flow of material to change from one of 5 a substantially continuous and uniform character to one of a variable character and, after passing through such apparatus, then to permit the flow of material to change back to one of a substantially continuous 10 and uniform character.

I am aware of the fact that it has been heretofore proposed to provide apparatus for treating or pasteurizing milk, cream or other liquids in which the milk was heated 15 to a pasteurizing temperature while flowing continuously, was then maintained at the pasteurizing temperature for a sufficient period of time to destroy or render innocuous the bacteria without cooking the albumen in the milk, and without the discontinuing of the flow of the milk while being heated, and then cooling the milk, as for example as disclosed in Letters Patent of the United States No. 684,319, to Frederick G. 20 Short, and I do not lay any claim broadly to a process of treating milk or other liquids and to apparatus such as set forth and disclosed in the said Short patent. On the contrary, I have sought to provide improved 25 apparatus for the treating of milk or other liquids by first heating it to a pasteurizing temperature, then holding it at that temperature for a predetermined time, and then cooling it.

It will be noted that all walls of the conduits and receptacles in the holding mechanism, with which any liquid to be treated may come into contact, are readily accessible 30 for the purpose of cleaning merely by disassembling adjacent parts or conduits. The importance of this in the sanitary handling of milk, for example, is well known. Further, it will be noted that the construction of the valve mechanism is such that liquid from 35 the source of supply always flows in one direction through the valve inlet duct to the vessel ducts, successively, and also always flows in one direction through the valve discharge duct from the vessel ducts, successively. This enables me to establish a definite and permanent relation between the source of supply and the inlet duct through 45 the valve mechanism and a definite and permanent relation between the outlet duct 50 through the valve mechanism and the discharge way.

To those skilled in the art of making apparatus of the class described, many alterations in construction and widely differing 55 embodiments and applications of my invention will suggest themselves, without departing from the spirit and scope thereof. My disclosures and the description herein are purely illustrative and are not intended to 60 be in any sense limiting.

What I claim is:—

1. In a system of the class described for pasteurizing milk and other liquids, the combination with a liquid heater and a liquid cooler, of a plurality of holding receptacles, means for conducting heated liquid from said heater to the lower ends of said receptacles to fill to the extent desired each of said receptacles, one after the other from its lower end, so that all the liquid held by each said receptacle will always enter it from the lower end thereof, and means for conducting said heated liquid from each said receptacle, after it has been held therein a predetermined time, to said cooler. 70

2. In a system of the class described for pasteurizing milk and other liquids, the combination with means for heating the liquid to be pasteurized as it flows in an attenuated stream, and a liquid cooler, of a plurality of holding receptacles, means for conducting heated liquid from said heating means to the lower ends of said receptacles to fill to the extent desired each of said receptacles, one after the other from its lower end, so that all the liquid held by each said receptacle always enters it from the lower end thereof, and means for conducting said heated liquid from each said receptacle, after it has been held therein a predetermined time, to said cooler. 80

3. In a system of the class described for pasteurizing milk and other liquids, the combination with a liquid heater and means for cooling said previously heated liquid 100 as it flows in an attenuated stream, of a plurality of holding receptacles, means for conducting heated liquid from said heater to the lower ends of said receptacles to fill to the extent desired each of said receptacles, one after the other from its lower end, so that all the liquid held by each said receptacle always enters it from the lower end thereof, and means for conducting said heated liquid from each said receptacle, after it 105 has been held therein a predetermined time, to said cooling means.

4. In a system of the class described for pasteurizing milk and other liquids, the combination with means for heating the liquid to be pasteurized as it flows in an attenuated stream and means for cooling said previously heated liquid as it flows in an attenuated stream, of a plurality of holding receptacles, means for conducting heated liquid from said heating means to the lower ends of said receptacles to fill to the extent desired each of said receptacles, one after the other from its lower end, so that all the liquid held by each said receptacle always 120 enters it from the lower end thereof, and means for conducting said heated liquid from each said receptacle, after it has been held therein a predetermined time, to said cooling means. 125

5. In a system of the class described for pasteurizing milk and other liquids, the combination with a liquid heater and a liquid cooler, of a plurality of holding receptacles, a combined filling and emptying duct for each said receptacle communicating at one end with said receptacle at its lower end, and having at its other end a combined inlet and discharge port, liquid conducting means extending from said heater and including an inlet duct having a discharge port arranged to register with said combined inlet and discharge ports of said combined filling and emptying ducts, one after the other, whereby the heated liquid always flows in one direction only through said inlet duct and then into the lower end of each of said holding receptacles to fill it to the extent desired, a discharge duct having an inlet port arranged to register with said combined inlet and discharge ports of said combined filling and emptying ducts, one after the other, a predetermined period after each said holding receptacle has been filled to the extent desired with heated liquid as aforesaid, and through which discharge duct the liquid from each said holding receptacle always flows in one direction only, and means for conducting the liquid discharged from said discharge duct to said cooler.
6. In a system of the class described for pasteurizing milk and other liquids, the combination with a liquid heater and a liquid cooler, of a plurality of holding receptacles, a combined filling and emptying duct for each said receptacle communicating at one end with said receptacle at its lower end, and having at its other end a combined inlet and discharge port, liquid conducting means extending from said heater and including an inlet duct having a discharge port arranged to register with said combined inlet and discharge ports of said combined filling and emptying ducts, one after the other, whereby the heated liquid always flows in one direction only through said inlet duct and then into the lower end of each of said holding receptacles to fill it to the extent desired, a discharge duct having an inlet port arranged to register with said combined inlet and discharge ports of said combined filling and emptying ducts, one after the other, a predetermined period after each said holding receptacle has been filled to the extent desired with heated liquid as aforesaid, and through which discharge duct the liquid from each said holding receptacle always flows in one direction only, means for conducting the liquid discharged from said discharge duct to said cooling means, and means for effecting communication between said discharge port of said inlet duct and said inlet port of said discharge duct, respectively, and said combined ports of said combined inlet and emptying ducts, one after the other.
7. In a system of the class described for pasteurizing liquid, the combination with means for heating the liquid to be pasteurized as it flows in an attenuated stream and means for cooling said previously heated liquid as it flows in an attenuated stream, of a plurality of holding receptacles, a combined filling and emptying duct for each said receptacle communicating at one end with said receptacle at its lower end, and having at its other end a combined inlet and discharge port, liquid conducting means extending from said heating means and including an inlet duct having a discharge port arranged to register with said combined inlet and discharge ports of said combined filling and emptying ducts, one after the other, whereby the heated liquid always flows in one direction only through said inlet duct and then into the lower end of each of said holding receptacles to fill it to the extent desired, a discharge duct having an inlet port arranged to register with said combined inlet and discharge ports of said combined filling and emptying ducts, one after the other, a predetermined period after each said holding receptacle has been filled to the extent desired with heated liquid as aforesaid, and through which discharge duct the liquid from each said holding receptacle always flows in one direction only, means for conducting the liquid discharged from said discharge duct to said cooling means, and means for effecting communication between said discharge port of said inlet duct and said inlet port of said discharge duct, respectively, and said combined ports of said combined inlet and emptying ducts, one after the other.

In testimony whereof I affix my signature in the presence of two witnesses.
